CLAIM

The ornamental design for a wall mounted diaper changing station, as shown and described.

DESCRIPTION

FIG. 1 is a right side perspective view of a wall mounted diaper changing station showing my new design;

FIG. 2 is a left side perspective view thereof;

FIG. 3 is a right side elevational view, the left side being a mirror image thereof;

FIG. 4 is a front elevational view thereof;

FIG. 5 is a top plan view thereof;

FIG. 6 is a perspective view in open condition;

FIG. 7 is a front perspective view thereof;

FIG. 8 is a right side elevational view thereof; and

FIG. 9 is a top plan view thereof.
